(57) **CLAIM**

The ornamental design for an umbrella holder as shown and described.

DESCRIPTION

FIG. 1 is an environmental front view of the present invention;

FIG. 2 is an environmental rear view of the holder thereof;

FIG. 3 is a left view of the holder thereof;

FIG. 4 is a front view of the holder thereof;

FIG. 5 is front perspective view of the holder thereof;

FIG. 6 is a rear view of the holder thereof;

FIG. 7 is a right view of the holder thereof;

FIG. 8 is a bottom view of the holder thereof;

FIG. 9 is an alternate environmental front view of the holder thereof; and,

FIG. 10 is a top view of the holder thereof.

The broken lines of FIGS. 1, 2, and 9 showing a person and an umbrella represent environment of the umbrella holder and form no part of the claimed design. The remainder of the broken lines represent stitching that does not form part of the claimed design.
